UNITED STATES PATENT OFFICE.

FRED MATHEWS, OF CHICAGO, ILLINOIS, ASSIGNOR TO CLINTON C. MURPHY, OF CHICAGO, ILLINOIS.

DEVICE FOR MANIPULATING COUPLING-PINS.

1,084,649.

Specification of Letters Patent.

Patented Jan. 20, 1914.

Application filed October 7, 1912. Serial No. 724,476.

To all whom it may concern:

Be it known that I, FRED MATHEWS, a citizen of the United States, residing at Chicago, in the county of Cook and State of Illinois, have invented certain new and useful Improvements in Devices for Manipulating Coupler-Pins, of which the following is a specification.

My invention relates to devices for manipulating the locking pins of railway car couplings, and the principal object of the invention is to provide a device of this sort which will have sufficient flexibility or capacity for self adjustment to enable the device to accommodate itself to the shifting movements of the coupling, both transverse and longitudinal with respect to the car, so that it will not be broken, bent or strained, or the pin accidentally raised by such movements of the coupling.

A further object of the invention is to provide a device of this character which will be extremely simple and economical in construction, and which may be operated from a position at one side of the car and by a movement in the direction away from the car; the purpose of the latter features being to prevent or minimize the injuries which trainmen frequently suffer in uncoupling railway cars.

The invention consists in certain simple but novel arrangements for carrying out the objects above stated.

The invention is illustrated, in a preferred embodiment, in the accompanying drawing wherein—

Figure 1 is a fragmentary end elevation of a railway car with the device of my invention attached thereto, Fig. 2, a sectional plan taken on line 2—2 of Fig. 1, Fig. 3, a view, in perspective, of the rocking device by the movement of which the pin is raised, and Fig. 4, a sectional plan taken on line 4—4 of Fig. 1.

Like characters of reference designate like parts in the several figures of the drawing.

Referring to the drawing, 10 designates the end of a railway car and 11 a coupler of the familiar automatic type provided with the usual locking pin 12.

The device for raising the locking pin consists of a rocking member or bell crank 13 and an operating or pull rod 14. Preferably these parts are loosely connected by

means of loops or eyes 15, 16 which may be formed in any suitable manner. The rocking member is formed with the preferably straight arm or projection 17 which extends through the eye 18 with which the locking pin 12 is provided. The rocking member is formed in any suitable manner with a perforation 19 through which extends the loop eye which is secured to the end of the car. The pin is raised by an outward pull upon 65 and lengthwise movement of the operating rod 14. The latter is preferably guided in a ring 22 on the end of the car.

It will be seen that the device for manipulating the pin has a floating relation to the 70 car and to the pin which permits the device to accommodate itself to the shifting movements of the coupling both transverse and longitudinal with respect to the car. If the arm 17 is perfectly horizontal, as my invention 75 contemplates by preference, in any side shift of the coupler the ring 18 will slide back and forth on the arm. If, however, the arm 17 should stand a trifle oblique to the horizontal, as may well happen for one 80 reason or another, the uncoupling device will accommodate itself to a side shift without pulling the pin because of the capacity of the rocking member to rock transversely of the car. The rocking member will swing 85 outwardly from the end of the car or inwardly toward the same on the ring 20 as the coupler shifts longitudinally. The connections of the operating rod 14 with the rocking member and its guide 22 are loose connections and the rod is not fixed or locked 90 in any manner so that it will follow and accommodate itself to the movements of the rocking member.

This device may be made very cheaply 95 and can be readily attached to any sort of railway car. Its capacity for self adjustment to the different shifting movements of the coupling both longitudinal and transverse, prevent it from being broken, bent or strained when these necessary movements of the coupling take place. The same capacity for self adjustment prevents the shifting of the coupler from withdrawing the pin. The locking pin of an automatic coupling has a 100 relatively short movement from its normal to its unlocking position, and consequently, unless the mechanism for raising the pin can adjust itself to the movements of the coupler, there is danger that such shifting 105 110

movement may raise the pin and so cause the accidental uncoupling of the car. Several of the pin manipulating mechanisms which have been heretofore devised have proven unserviceable for this reason. Moreover, when the pin is in the normal or rocking position no part of the uncoupling mechanism projects from the outer edges of the car body either at the side or below the car.

10 The mechanism is manipulated to raise the pin by an outward pull away from the car instead of the usual crank or lever movement. The trainman does not have to reach between the cars or under either of them.

15 For these reasons the device insures a greater degree of safety than any of the uncoupling mechanisms of which I am aware.

I claim:

1. The combination with the locking pin 20 of a car coupling provided with an eye, of an operating rod formed at one end with an eye, a guide on the car through which said rod extends, a bell crank having an arm adapted to extend through the eye of said 25 coupler pin, an arm formed at its extremity with an eye loosely engaging with the eye on said operating rod, said bell crank being provided at the junction of said arms with a perforation, and an eye on the end of the car which extends through said perforation 30 pivotally connecting the bell crank with the car so as to allow movement of the bell crank both transversely of the car and to and from the same.

35 2. A device for manipulating the locking pin of a railway car coupling comprising a bell crank, one arm of which is engaged with said locking pin, a pull rod, movable in the

direction of its length and on the end of the car, loosely connected to the other arm of 40 said bell crank, said bell crank being provided intermediate its ends with a perforation, and an eye on the end of the car which extends through said perforation pivotally connecting the bell crank with the car so as 45 to allow movement of the bell crank both transversely of the car and to and from the same.

3. The combination with the locking pin 50 of a car coupling provided with an eye, of an operating rod, a guide on the car through which said rod extends, a bell crank having an arm adapted to extend through the eye of said coupler pin, and an arm which is loosely connected with the end of said operating rod, and means for attaching the bell crank to the end of the car which permits it to rock both transversely of the car and also to and from the end of the same.

4. The combination with the locking pin 60 of a car coupler, of a bell crank engaged with said locking pin which is attached to the end of the car so that it may rock transversely of the car and also longitudinally of the same, and an operating element for rocking said bell crank to raise said locking pin 65 which is loosely connected with said bell crank and with the car so as not to hinder said bell crank from rocking on its fulcrum both longitudinally and transversely with 70 the forward and back and sidewise movements of the coupler.

FRED MATHEWS.
